GILL-DRAWING MACHINE

Ralph C. Berker, Hoxsie, R. I.

Application July 3, 1948, Serial No. 36,845

9 Claims. (Cl. 19—129)

1

This invention relates to a gill-drawing machine and the like, particularly to the front nip-rollers thereof.

It is desirable to mount the front nip-rollers in a gill-drawing machine close to the combs or faller bars in order to control short staple in the material passing through the combs thereby eliminating subsequent drawing operations of the material. It is also desirable to mount the nip-rollers in a manner whereby access to the rollers may be quickly and readily had. Further, it is desirable to provide a set of nip-rollers as a unit structure which may be comparatively easy to attach to existing gill-drawing machines.

An object of the invention is the provision of a set of nip-rollers and mounting therefor which is so constructed as to secure the advantages mentioned above.

A more specific object of the invention is the provision for mounting the upper of the nip-rollers of a gill-drawing machine in a manner that the same may be quickly and easily removed from the lower nip-roller so as to permit access to the lower roller for removing lap therefrom or replacement.

With these and other objects in view, the invention consists of certain novel features of construction, as will be more fully described and particularly pointed out in the appended claims.

In the accompanying drawings:

Figure 1 is a front elevational view of a gill-drawing machine embodying my invention.

Figure 2 is a sectional view taken substantially on line 2—2 of Figure 1 and on an enlarged scale; and

Figure 3 is an end view looking toward the machine in the direction of the arrows on line 3—3 of Fig. 1, showing the relationship between the front drawing rollers and the fallers and the drive therefor.

In carrying out the invention I provide a set of front draft rollers comprising two spaced lower fluted rollers and a top or pressure roller. The pressure roller is positioned to engage both fluted rollers so as to distribute the pressure thereof between the two lower rollers and on the bearings thereof. The fluted roller next to the combs is of less diameter than the other and substantially smaller than the usual fluted draft roller heretofore employed in gill machines. The pressure roller is so related to the smaller fluted roller that it does not extend materially beyond the smaller roller which permits the draft rollers to be positioned substantially nearer the needles of the combs than what has heretofore been possible by the construction of draft or nip-rollers em-

ployed in gill machines. In the usual construction the distance between the nip of the rollers and the combs is approximately one and seven-eights of an inch, while the construction herein disclosed, the distance between the nip of the rollers and the needles has been shortened to approximately seven-eighths of an inch which is ample to control short fibers leaving the combs and thereby eliminating subsequent drawing operations of the material.

The top or pressure roller is mounted on a frame or the like which is pivotally secured at the lower end thereof to the bearing blocks in which the fluted rollers are journaled. This provides a mounting for the top roller which may be moved to swing the top roller from the fluted rollers to a position in front thereof so as to permit quick access to the fluted rollers when necessary. By mounting the supporting frame of the top roller on the bearings of the fluted roller, I provide a unit structure which may be quickly assembled and attached in position or which may be substituted as a unit to replace the usual nip-rollers of a machine and thereby enhance the efficiency of the machine.

Referring to the drawings for a more detailed description of the invention, 10 designates generally a gill-drawing machine having two sets of faller bars 11 and 12 (see Figure 2) which are arranged with their pins intersecting to adapt them to be traversed in the same direction during their working stroke and then returned in the opposite direction at a different level to be again traversed in the first direction. The traversing motion of the faller bars 11 and 12 is accomplished by two pairs of traverse screws 13, 14, 15, and 16 on one side of the machine and a similar two pairs of screws on the other side of the machine with the threads of the screws engaging the ends of the fallers to slide them on horizontal saddles 17, 18, 19, and 20 on one side of the machine and similar saddles on the other side of the machine. The two screws 13 and 15 operate to traverse the two sets of faller bars during their work stroke. At the end of the work stroke the faller bars are transferred by means of cams or hammers (not shown) to the lower and upper screws 14 and 16 to be traversed in the opposite direction. At the end of the return stroke the faller bars are transferred back to the screws 13 and 15 by cams or hammers (not shown) to be again traversed in the first direction.

The traverse screws 13, 14, 15, and 16 are suitably journaled in bearing blocks 21 and 22 formed as part of or attached to the side frames 23 and

24 of the machine. Motion is transmitted to the several traverse screws by means of drive shafts 25 adapted to be driven from any suitable source of power. There are two of these drive shafts, one on each side of the machine, and each may be a continuation of or attached in any suitable manner to the lower screws 14. Each shaft 25 carries a spur gear 26 engaging with a similar gear 27 on a screw 13 and the gear 27 in turn engages with a similar gear 28 on the adjacent screw 15. The gear 28 also engages a similar gear 29 on the uppermost screw 16 whereby the four screws on one side of the machine are connected to be driven by a drive shaft 25, while the four screws on the other side of the machine are similarly connected and driven by the other drive shaft 25.

All the traverse screws are driven in unison at the same rate of speed, and the screws 13 and 15 which traverse the fallers 11 and 12 respectively during the work stroke thereof have their thread grooves (not shown) so related that the fallers of one set are advanced thereby in staggered relation with the other set of fallers with the pins of the fallers penetrating into the material from opposite directions and traversing through the fibers to straighten and lay them parallel, all in a manner usual in machines of this construction. The material that is being worked upon is usually drawn from the comb or faller bars by means of a pair of front drawing or nip-rollers. A set of these nip-rollers usually consist of two rollers, one mounted above the other whereby when pressure is applied to the top roller, as is usual, the force is also applied directly upon the bearing of the lower roller.

In accordance with the present invention, I provide a set of drawing or nip-rollers designated generally 38 which comprises two fluted lower rollers 31 and 32 and a smooth upper or pressure roller 33 positioned to rest upon both rollers 31 and 32. The roller 31 is employed as the drive shaft for the roller 32, and for this purpose it is constructed with a reduced spindle 34 which extends axially from one end thereof and a reduced spindle 35 which extends axially from the other end of the roller. The spindles 34 and 35 are journaled in cap bearing blocks designated 36, which are similar to each other and are secured to the sides 23 and 24. Each bearing block has a depending arm 37 thereon which is provided with a longitudinal opening 38. The arm 37 is slidably mounted on a bracket 39 having a foot 40 provided with a threaded opening 41 through which extends an adjusting screw 42 to bear against the lower end of the arm 37. Turning the screw 42 will raise or lower the bearing block 36 depending upon the direction of rotation of the screw 42 whereby alignment of the bearing blocks may be had. A check nut 43 locks the screw 42 in position. The arm 37 of each bearing 36 is secured to the sides of the machine by bolts 44 which extend through the sides, the bracket, and opening 38. A nut 45 engages the bolt to secure the parts together in a usual manner. The roller 32 is similarly constructed with reduced spindles 46 and 47 which extend axially from the ends and are journaled in the bearing blocks 36.

The spindle 35 carries a gear wheel 50 to be driven through any suitable power source. The spindle 34 carries a spur gear 51 which engages an intermediate spur gear 52 suitably mounted on a stud 53 secured in a bearing block 36. The

intermediate gear 52 in turn engages a spur gear 54 on the spindle 46 whereby connecting rollers 31 and 32 to rotate in the same direction. The roller 31 is of a smaller diameter than the roller 32 and, accordingly, gears 51 and 54 are chosen such that the surface speed of the rollers 31 and 32 will be equal to each other.

The top roller 33 is constructed with reduced spindles 55 which extend axially from the ends thereof which are journaled in bearing blocks 56 each of a similar construction and having a projection 57 extending laterally of the opening therein. These blocks 56 are mounted on a frame designated generally 58, which comprises spaced arms 59 which are tied at the upper end thereof by a cross brace 60. Each arm is of a similar construction and has a right angularly extending portion 61 at the upper end thereof which extends inwardly towards the faller bars 20 and is provided with an opening 62. The lower portion 63 of the arm extends inwardly in an inverted goose-neck formation (see Figure 2), the end extremity of which has a bearing opening 64. Each arm is also provided with a recess 25 65 that extends lengthwise of the arm on the inner side thereof. An elongated opening 66 extends through the rear wall of the recess 65 from the opposite side of the arm, substantially the entire length of the recess 65. The frame 30 58 is attached to the machine by pivotally mounting each arm on the bearing blocks 36 by means of stud pins 67 which extend inwardly from the bearings 36 at a position beneath the rollers 31 and 32. Thus the frame is mounted 35 on the bearing blocks 36 in a manner that the frame may be swung about its mounting, as indicated in dot and dash line 68 (see Figure 2) so as to swing the top roller 33 away from the rollers 31 and 32 whereby access to these lower 40 nip rollers may be had when desired.

In order to provide a control pressure of the nip of the rollers on the material passing through the rollers, the bearing blocks 56 are slidably mounted on the arms 59. Each bearing block 56 is constructed similar to the other and is mounted in a like manner on one of the arms 59 and extends into the recess 65 in the arm in sliding relation with the walls thereof with the projection 57 passing through the opening 63 to project a slight distance beyond the arm. A screw bolt 69 threadedly engages the projection 57 to slidably secure the bearing 56 to the arm. A washer 70 or the like is interposed between the head of the bolt and the projection, as is usual in connections of this character. A threaded member 71 having a handle 72 secured or otherwise provided at the upper end thereof passes loosely through the opening 62 in the portion 61, and the end thereof rests on the bearing block 56. A nut or abutment 73 in the form of a rectangular block has a threaded opening 74 and is slidably mounted on the walls of the recess 65. The member 71 threadedly extends through the opening 67. Rotating the member 71 will slidably move the abutment 73 to or from the block 56 depending upon the direction of rotation of 71. A compression spring 74 encircles the member 71 and has the lower end resting against the abutment 73 and the upper end against the portion 61. Thus the member 71 is yieldingly forced into engagement with the bearing 56 to apply a pressure thereto. The pressure applied is controlled by rotating the member 71 in the proper direction. A locking member 75 encircles member 71 and has a depending portion 76 which

extends into engagement with the end 61. A set screw or the like 77 detachably secures member 11 to member 15 whereby to prevent accidental free turning thereof.

The material being acted upon and passing through the nip-rollers may be collected in any suitable manner. In the present instance I have shown a so-called coiler can device designated generally 78 having a suitable guide 79 through which the material is guided between rollers 80 and 88 to pass therefrom into a can 81. The can 81 rests upon a revolving platform 82 to be engaged thereby to rotate the same. The platform may be rotated in any suitable manner and is herein shown as being provided with a gear wheel 83 which is driven by means of a driving pinion 84 which may be rotated from any suitable source of power.

It now will be apparent that I have disclosed a nip-roller construction and mounting therefor which adapts the rollers to be positioned closer to the needles of the faller bars and wherein the top roller 33 may be easily removed from engagement with the rollers 31 and 32 by merely rotating the handle 72 to relieve the pressure thereon, and thereafter the frame 58 may be swung out of position to permit access to the rollers 31 and 32. It will also be apparent that this front set of rolls and its supporting structure is also adapted to be employed as a unit which may be easily attached to a gill-machine for replacing the usual nip-rollers thereof.

I have shown by way of example a construction of nip-rollers wherein the pressure roller directly contacts the fluted rollers. However, the invention also contemplates the use of an apron placed about the pressure roller as is usual in certain types of gill-machines.

I claim:

1. In a machine of the type specified, a set of nip-rollers comprising a pair of rotatably mounted fluted rollers, a top roller engaging both of said fluted rollers, a frame pivotally mounted on said machine, bearings slidably mounted on said frame, said top roller being journaled in said bearings, resilient means carried by said frame for applying a pressure on said bearings to yieldably move said top roller into engagement with said fluted rollers, said frame being movable to swing said top roller to and away from said fluted rollers.

2. In a gill-drawing machine, a plurality of faller bars, a set of nip-rollers for drawing the material from the faller bars comprising a pair of spaced rotatably mounted fluted rollers, a top roller engaging both of said fluted rollers providing a bite between said top roller and each of said fluted rollers, a frame, means for rotatably mounting said top roller on said frame and means for pivotally mounting said frame on said machine for movement thereof for swinging said top roller to and away from said fluted rollers to permit access to said fluted rollers.

3. In a gill-drawing machine, a plurality of faller bars, a set of nip-rollers for drawing the material from the faller bars comprising a pair of spaced rotatably mounted fluted rollers, a top roller engaging both of said fluted rollers providing a bite between said top roller and each of said fluted rollers, a generally vertical frame pivotally mounted on said machine, spaced bearings carried by said frame, said top roller being journaled in said bearings and yieldable means carried by said frame for applying a yielding

pressure to said top roller, said frame being movable about its pivot to move said top roller away from the said fluted rollers to a position sufficiently spaced from said fluted rollers to permit access thereto.

4. In a gill-drawing machine, a plurality of faller bars, a set of nip-rollers for drawing the material from the faller bars comprising a pair of spaced rotatably mounted fluted rollers, a top roller engaging both of said fluted rollers providing a bite between said top roller and each of said fluted rollers, a frame pivotally mounted on said machine, spaced bearings slidably carried by said frame, said top roller being journaled in said bearings, and means including a compression spring for applying a pressure to said top roller, said frame being movable to move said top roller to and away from said fluted rollers for access thereto.

5. In a gill-drawing machine, upper and lower nip-rollers, means for mounting said upper roller comprising a generally vertical frame pivoted at the lower end portion thereof on said machine, spaced bearings slidably carried on said frame, said upper roller being journaled in said bearings, spaced movable abutments carried by said frame and having a threaded opening therein, a threaded member extending through each abutment and into engagement with one of said bearings and a compression spring engaging each of said abutments for applying a pressure through said threaded members and said bearings to said top roller.

6. A unit nip-roller assembly for a gill-drawing machine comprising two lower fluted rollers, a bearing block at each end of said rollers, said rollers being journaled in said bearing blocks, means for detachably securing said bearing blocks to the sides of the machine, a frame pivotally mounted on said bearing blocks and a top roller journaled in said frame and movable in and out of engagement with said fluted rollers.

7. A unit nip-roller assembly for a gill-drawing machine comprising two lower fluted rollers, a bearing block at each end of said rollers, means for detachably securing said bearing blocks to the sides of the machine, said rollers being journaled in said bearing blocks, a generally vertical frame pivotally mounted at the lower end thereof on said bearing blocks for swinging movement relative thereto, spaced bearings slidably carried by said frame, a top roller journaled in said bearings and movable in and out of engagement with said fluted rollers.

8. In a machine of the type specified, a set of nip-rollers comprising a pair of rotatably mounted lower rollers and an upper roller for applying a pressure on material passing over said lower rollers, a frame pivotally mounted on said machine at a location beneath said lower rollers, means for rotatably and slidably mounting said upper roller on said frame, and resilient means carried wholly on said frame for applying a pressure on said upper roller to yieldably move the same into engagement with said lower rollers, said frame being movable to swing said upper roller to and away from said lower rollers.

9. In a gill-drawing machine, a set of nip-rollers, comprising a pair of rotatably mounted lower rollers and an upper roller for applying a pressure on material passing over said lower rollers, a frame pivotally mounted on said machine at a location beneath said lower rollers, means for rotatably and slidably mounting said upper roller on said frame, and adjustable

spring means carried wholly by said frame for applying a pressure on said upper roller to yieldably move the same into engagement with said lower rollers, said frame being movable to swing said upper roller to and away from said lower rollers.
